(57) **CLAIM**

The ornamental design for a camping light, as shown and described.

DESCRIPTION

FIG. 1 is a front perspective view of a camping light of the present disclosure according to one embodiment;

FIG. 2 is a rear perspective view of the camping light shown in FIG. 1;

FIG. 3 is a front elevational view of the camping light shown in FIG. 1;

FIG. 4 is a rear elevational view of the camping light shown in FIG. 1;

FIG. 5 is a left-side elevational view of the camping light shown in FIG. 1;

FIG. 6 is a right-side elevational view of the camping light shown in FIG. 1;

FIG. 7 is a top plan view of the camping light shown in FIG. 1;

FIG. 8 is a bottom plan view of the camping light shown in FIG. 1;

FIG. 9 is a front perspective view of a camping light of the present disclosure according to another embodiment;

FIG. 10 is a rear perspective view of the camping light shown in FIG. 9;

FIG. 11 is a front elevational view of the camping light shown in FIG. 9;

FIG. 12 is a rear elevational view of the camping light shown in FIG. 9;

FIG. 13 is a left-side elevational view of the camping light shown in FIG. 9;

FIG. 14 is a right-side elevational view of the camping light shown in FIG. 9;

FIG. 15 is a top plan view of the camping light shown in FIG. 9; and,

FIG. 16 is a bottom plan view of the camping light shown in FIG. 9.

The broken lines shown in the drawings are for the purpose of illustrating portions of the camping light that form no part of the claimed design.
